WALL BROILER OR THE LIKE

Joel A. Del Francia, Los Angeles, Calif.

Application June 24, 1957, Serial No. 46,718

Term of patent 14 years

(Cl. D81—10)

FIG. 1.

FIG. 2.

FIG. 3.

Fig. 1 is a perspective view of a wall broiler or the like, showing my new design;

Fig. 2 is an elevational view thereof illustrating the side opposite that shown in Fig. 1; and

Fig. 3 is a top plan view of the broiler.

The back of the broiler is plain.

I claim:

The ornamental design for a wall broiler or the like, substantially as shown and described.
